Chiliion F. Brown

UNITED STATES PATENT OFFICE.

C. F. BROWN, OF BRIDGEPORT, CONNECTICUT.

SPRING-ROLLER FOR WINDOW-SASH.

Specification of Letters Patent No. 26,830, dated January 17, 1860.

To all whom it may concern:

Be it known that I, CHILLION F. BROWN, of the city of Bridgeport, county of Fairfield, and State of Connecticut, have invented a new and useful Sash-Supporter for Windows; and I do hereby declare that the following is a full and exact description thereof, reference being had to the accompanying drawings and to the letters of reference marked thereon.

The nature of my invention consists in attaching to one of the sides of the window sash next to the window frame, two rollers with springs attached thereto, one of which is to be so set in a cavity of the proper size near the top of the sash, and the other in a cavity near the bottom of the sash—that the springs will constantly press the rollers against the sills of the window frame and thus prevent the sash from settling, as well as facilitate the raising and lowering of the same, and at the same time prevent the sash from dropping down when left up at any desired height.

To enable others skilled in the art to make and use my invention I will describe its construction and operation.

Figure 1, represents the window sash and frame with the spring rollers attached to the sash.

Fig. 2, represents the spring roller in which B, is a metallic frame to which the axis C, is attached upon which the metallic roller D revolves E, E, are metallic springs, one end of each of which rests upon the cross bar F, of the frame B, and is secured to said frame by a rivet G, the springs being so shaped and attached that the whole arrangement will resemble one half of an ordinary elliptic spring.

Fig. 3, is a side view of the spring supporter.

What I claim as new as sash supporters, and desire to secure by Letters Patent, is—

The combination of the frame B, in which the roller revolves with the two springs E, E, substantially as described.

CHILLION F. BROWN.
